UNITED STATES PATENT OFFICE

ALFRED L. KRONQUEST, OF SYRACUSE, NEW YORK, ASSIGNOR TO CONTINENTAL CAN COMPANY, INC., OF NEW YORK, N. Y., A CORPORATION OF NEW YORK

PACKER FOR MACHINES FOR CLOSING CONTAINERS

Application filed December 5, 1930. Serial No. 500,385.

The invention relates to new and useful improvements in a machine for closing containers and more particularly to the packer associated therewith for pressing down the floating food product in the container preparatory to the covering and sealing of the same.

An object of the invention is to provide a packer which moves continuously and which operates upon the containers for depressing the floating food products therein regardless of the timing of the container as it travels beneath the packer.

A further object of the invention is to provide a packer of the above type which is in the form of an endless traveling belt positively driven and moving in a path inclined to the path of travel of the container so that as the container passes beneath said belt the food product will be depressed to a position level with the top of the container.

In the drawings, which show by way of illustration one embodiment of the invention:

Fig. 1 is a side view of a portion of the machine embodying the improvements.

Fig. 2 is a view partly in section and partly in end elevation of the same.

Fig. 3 is a sectional view on the line 3—3 of Fig. 1.

Fig. 4 is a diagrammatic view showing the container as passing from beneath the packer under a retainer plate which maintains the food product in a depressed condition until the end or cover-applying station is reached.

It has been a common expedient to provide seaming machines for closing containers with means in timing therewith for depressing the floating food product into the container prior to the applying of the cover thereto. The present invention has to do with an improved construction of packer associated with a machine for closing containers after the food product has been placed therein. The containers filled with the food product are fed by an endless traveling conveyor into the machine which applies a cover thereto and seams the cover to the container body. A machine for closing the containers

has not been shown as it may be of any desired construction.

The conveyor which conveys the container to the closing machine moves the filled containers along a supporting bed or trackway therefor. Associated with this supporting bed is a packer which consists of an endless belt slightly wider than the diameter of the can which passes beneath the same. This belt is mounted on a supporting bracket so that it travels in an inclined plane. The outer end of the traveling packer is higher than the inner end so that the containers with the floating food product therein will readily pass under the high end of the traveling packer belt. This packer belt is driven in timing with the conveyor which carries the containers along the supporting bed. The low end of the packer belt is of sufficient height so that the can body itself makes substantial contact therewith as the container passes from beneath the packer belt.

Attached to the machine for closing the containers is a supporting bed consisting of angle irons 3, 3, the outer end of which is attached to a supporting standard 2. Upon this supporting bed 3, 3 are mounted wear plates 4, 4. The containers which are indicated at C are adapted to slide along these wear plates, resting thereon. Guide rails 5, 5 are provided for directing the cans along the wear plates 4. The containers are moved along the wear plates 4, 4 by a traveling conveyor chain 6 which is provided with spaced dogs 7. This conveyor chain runs over bars 8 supported by the angle plates 3, 3. It also runs over a sprocket wheel 9 at the entering end of the machine and over a driving sprocket wheel 10 located on the bed between the packer and the cover applying station. Said sprocket 10 is driven from the closing machine. The sprocket chain also runs over a sprocket 11 and idler sprockets 12 and 13. The idler 12 as shown in Fig. 3 of the drawings, is mounted for free rotation on a stub shaft 14 which is clamped to a depending portion of the frame by means of a nut 16. The idler sprockets 9 and 13 are carried by suitable shafts which are like-

wise supported by the frame but for the purpose of illustration the supporting parts have been omitted from Fig. 1 of the drawings.

- 5   Mounted on the bed 3, 3 of the machine is a supporting member 1 carrying a bracket 14^a. Said bracket 14^a carries a standard 15^a which is adjustably attached thereto by bolts 16, 16 passing through slots 17, 17 in the standard and threaded into the bracket 14^a.
- 10   At the upper end of this standard 15^a is a supporting head 18, said supporting head being bolted to the upper end of the standard by bolts 19, 19. Mounted in this supporting head is a shaft 20. The shaft 20 is provided with a sprocket wheel 21 adjacent the standard 15^a. Also mounted on this shaft 20 is a pulley having spaced flanges between which a belt 22 runs. Mounted on the head 18 are projecting arms 23. There is an arm at each side of the head 18 and at each side of the belt. Connecting the arms 23 is a supporting member 24 which has a cylindrical bore extending lengthwise thereof and disposed in this bore is a rod 25. The rod 25 is reduced in section so that a spring 26 housed within the bore and bearing against the inner end of the bore will also bear against a shoulder on the rod and normally force the rod outwardly. A cross-head 27 is mounted on this rod 25 and is provided with spaced bearings 28 in which is mounted a pulley 28^a over which the belt 22 runs. The cross-head 27 is provided with guide rollers 29, 29 which are grooved to receive the edges of the belt 22. The head 18 also carries grooved guide rollers 30, 30 which engage the side edges of the lower strand of the belt at a point adjacent the head 18.
- 15   A sprocket chain 31 runs over the sprocket wheel 21 and also over the sprocket wheel 32 carried by the shaft 33 which supports the sprocket 11. The conveyor chain 6 drives the sprocket 11 and said sprocket 11 drives the shaft 33 and the sprocket 32. An idler sprocket 34^a is carried at the outer end of the arm 35 which is mounted on the frame so that the arm may be shifted to take up the slack of the sprocket chain 31. Said arm 35 is held clamped in adjusted positions by a clamping bolt 36 which passes through a slot 37 in the arm and is threaded into a lug carried by the supporting member 1 of the machine.
- 20   Through the aid of the sprocket chain 31 the shaft 20 is positively rotated and this causes the belt 22 to travel in the direction of the arrow in Fig. 1. It will be noted that the outer end of the belt running over the pulley mounted in the bearings 28, 28 is spaced a greater distance above the bed than the inner end of the belt running over the pulley on the shaft 20. This belt is the packing belt which depresses the floating food product in the containers. The spring 26 keeps the belt under tension so that it is

70   moved at the speed of the pulley driven by the shaft 20 and this pulley is preferably timed so that the surface speed of the belt as it comes in contact with the container is substantially the same as the speed of travel of the conveyor 6 which moves the container along the supporting bed. The belt only makes light contact with the top of the container as it passes beneath the lower end of the belt. There is a plate 38 underneath which the container is carried by the conveyor 6 and this plate maintains the food product depressed until the container reaches the cover applying station. This plate 38 is attached to the standard 15^a and is adjustable 80 with the standard so that when the standard is raised or lowered for different size containers, or for properly placing the belt so that it will permit the container to pass underneath the same, the plate is likewise adjusted to a proper position to permit the container to pass underneath the same and maintain the food product therein depressed in the container until it reaches the cover supplying means.

85   90

95   As shown in Figures 1 and 4 of the drawings, the food product appears projecting above the containers as they are fed beneath the packer belt and the belt will engage the food product and gradually depress the same as it travels along with the belt until it is fully depressed beneath the plane of the flange of the container.

100   When it is desired to use the packer in connection with cans of different heights than those shown, the bolts 16 can be loosened and the bracket raised or lowered. The arm 35 is released so as to give up slack if necessary to the chain and may be adjusted to take up the slack for different set positions of the packer.

105   It is obvious that minor changes in the details of construction and the arrangement of parts may be made without departing from the spirit of the invention as set forth in the appended claims.

110   Having thus fully described the invention, what is claimed as new and is desired to be secured by Letters Patent is:

115   1. The combination of a supporting bed, means for conveying containers along said supporting bed, means for depressing the food product in the containers as they travel along said bed, including a traveling belt arranged so as to move in a plane inclined to the path of travel of the container and disposed so that the container as it is moved beneath the belt will be caused to gradually approach the belt and the belt to make contact with the food product for depressing the same in the container and means associated 120 with said traveling belt for holding the food product depressed in the container after it leaves the belt.

125   2. The combination of a supporting bed, means for conveying containers along said 130

supporting bed and means for depressing the food product in the containers as they travel along said bed, including a traveling belt arranged so as to move in a plane inclined to the path of travel of the container and disposed so that the container as it is moved beneath the belt will be caused to gradually approach the belt and the belt to make contact with the food product for depressing the same in the container, said belt being mounted on a standard adjustably attached to the bed so that it may be bodily raised or lowered for operating upon cans of different heights.

3. The combination of a supporting bed, means for conveying containers along said supporting bed and means for depressing the food product in the containers as they travel along said bed, including a traveling belt arranged so as to move in a plane inclined to the path of travel of the container and disposed so that the container as it is moved beneath the belt will be caused to gradually approach the belt and the belt to make contact with the food product for depressing the same in the container, said belt being mounted on a standard adjustably attached to the bed so that it may be bodily raised or lowered for operating upon cans of different heights, and means for driving said belt, including devices for permitting the raising or lowering of the belt.

4. The combination of a supporting bed and means for conveying containers along said supporting bed, including a conveyor chain and means for depressing the food product in the containers as they travel along said bed, including a belt arranged so as to move in a plane inclined to the path of travel of the container, a standard, a head carried by said standard and devices supported by said head over which the belt travels, said devices including yielding means for placing said belt under tension, and means for driving said belt, said belt being disposed so that the container as it is moved beneath the belt will be caused to gradually approach the belt and the belt make contact with the food product for depressing the same in the container.

5. The combination of a supporting bed, means for conveying containers along said supporting bed and means for depressing the food product in the container, including a traveling belt, a standard, a head carried by said standard, devices mounted on the head for supporting said belt, said devices including yielding means for placing the belt under tension and guide rollers for engaging the edges of the belt for preventing the belt from moving laterally, said belt being inclined to the path of travel of the container and disposed so that the container as it travels beneath the belt will be caused to gradually approach the belt and the belt to make contact with the food product for depressing the same in the container.

6. The combination of a supporting bed, means for conveying containers along said supporting bed, means for depressing the food product in the containers as they travel along said bed including a standard, means for supporting said standard whereby it may be raised and lowered, a supporting head carried by said standard, a shaft carried by said head, a pulley mounted on said shaft, means for rotating said shaft, arms projecting laterally from the standard and inclined upwardly and outwardly from the standard relative to the path of travel of the containers, a pulley mounted at the outer end of said arms and a belt running over said pulleys and so disposed relative to the travel of the containers as to contact with and depress the floating food product therein.

7. The combination of a supporting bed, means for conveying containers along said supporting bed, means for depressing the food product in the containers as they travel along said bed including a standard, means for supporting said standard whereby it may be raised and lowered, a supporting head carried by said standard, a shaft carried by said head, a pulley mounted on said shaft, means for rotating said shaft, arms projecting laterally from the standard and inclined upwardly and outwardly from the standard relative to the path of travel of the containers, a pulley mounted at the outer end of said arms and a belt running over said pulleys and so disposed relative to the travel of the containers as to contact with and depress the floating food product therein, said arms being made with telescoping sections and a spring associated therewith whereby the pulleys are yieldingly forced away from each other for maintaining said belt under tension.

In testimony whereof, I affix my signature.
ALFRED L. KRONQUEST.
